UNITED STATES PATENT OFFICE.

CHARLES BESSER, OF MINONK, ILLINOIS.

NUT-LOCK.

1,158,163.

Specification of Letters Patent.

Patented Oct. 26, 1915.

Application filed May 7, 1915. Serial No. 26,591.

To all whom it may concern:

Be it known that I, CHARLES BESSER, a citizen of the United States, residing at Minonk, in the county of Woodford and State 5 of Illinois, have invented certain new and useful Improvements in Nut-Locks; and I do hereby declare the following to be a full, clear, and exact description of the invention, such as will enable others skilled in the art 10 to which it appertains to make and use the same.

This invention has for its primary object to provide a simple and efficient nut lock especially designed for locking a plurality 15 of nuts against rotation including essentially an attaching plate and nut engaging members movable longitudinally with relation to said plate whereby the locking members may be adjusted to co-act with nuts 20 spaced various distances apart.

With this and other objects in view, the invention consists in the novel construction, arrangement and formation of parts as will be hereinafter specifically described, claimed 25 and illustrated in the accompanying drawing, in which:

Figure 1 represents a perspective view of the improved nut lock applied to use in connection with the rails of a railroad. Fig. 2 30 represents a vertical sectional view through the nut lock. Fig. 3 represents a fragmental longitudinal sectional view therethrough.

Referring to the drawing in detail, wherein similar reference numerals designate corresponding parts throughout the several views, the numeral 5 indicates the attaching plate of the nut lock, which is provided with apertures or eyelets 7 adapted to receive the hooks 7^a carried by the base or railroad rail 40 supporting plate 6. A notch 8 is formed centrally of the lower longitudinal edge of the plate 5 and is adapted to receive a suitable tool, whereby the plate may be forced to the desired position with relation to the object 6 to which it is attached. Adjacent the upper longitudinal edge of the plate 5 is formed with a plurality of longitudinal slots or openings 9 corresponding in number to the number of nuts 10 to be locked.

50 The locking members designated generally by the numerals 11 include the horizontal medial portions 12 and upstanding and de-

pending angularly disposed ends 13 and 14 respectively. The downwardly directed portions 14 of the locking members are provided 55 with rivets 15 which extend through the slots 9 in the attaching plate 5 and permit sliding movement of the locking members with relation to the attaching plate 5. The upwardly directed ends 13 of the locking 60 members are formed with recesses defining pairs of spaced parallel tongues 16 adapted to engage on opposite sides of the nuts 10 to lock the latter against rotational movement.

As clearly illustrated in Fig. 1 each of 65 the locking members 11 is provided with two rivets 15, which are slidably received within the corresponding slot 9 in the plate 5, whereby rocking motion of the locking members with relation to the attaching plate 70 is prevented.

In the accompanying drawing the nut lock is shown applied to use in connection with the rails of a railroad for locking the nuts 10 of the bolts 17 which secure the fish plates 18 75 of the rails in position, but it will be understood that the nut lock is not necessarily limited to such use.

What I claim is:

1. A nut lock including an attaching plate 80 having a plurality of spaced longitudinal slots adjacent one edge thereof, a plurality of angular nut-engaging and locking members, and means rigidly secured to said angular nut-engaging and locking members slidably received within said slots.

2. A nut lock including an attaching plate having a plurality of spaced longitudinal slots adjacent one edge thereof, a plurality of angular locking members, and a pair of 90 rivets rigidly secured to each angular nut-engaging and locking member slidably received within each slot.

3. A nut lock including a base plate, a plurality of hooks secured to one longitudinal 95 edge of said base plate, an attaching plate having a plurality of apertures receiving said hooks, and a plurality of nut-engaging and locking members carried by said attaching plate.

4. A nut lock including a base plate, a plurality of hooks secured to one longitudinal edge of said base plate, an attaching plate having a plurality of apertures receiv-

ing said hooks and having a plurality of spaced longitudinal slots engaging the upper edge thereof, a plurality of angular nut-engaging and locking members, and means rigidly secured to said angular nut-engaging and locking members slidably received within said slots.

In testimony whereof I affix my signature in presence of two witnesses.

CHARLES BESSER.

Witnesses:

JOHN C. DANFORTH,
J. A. MINGERS.
